UNITED STATES PATENT OFFICE.

FREDERICK JULYAN, OF CHICAGO, ILLINOIS, ASSIGNOR, BY MESNE ASSIGNMENTS, TO THE AMERICAN MULTIGRAPH COMPANY, OF CLEVELAND, OHIO, A CORPORATION OF OHIO.

PAPER-FOLDING MACHINE.

1,046,193.

Specification of Letters Patent.

Patented Dec. 3, 1912.

Application filed December 19, 1908. Serial No. 468,305.

To all whom it may concern:

Be it known that I, FREDERICK JULYAN, a citizen of the United States, residing at Chicago, in the county of Cook and State of Illinois, have invented certain new and useful Improvements in Paper-Folding Machines, of which the following is a specification, reference being had to the accompanying drawings.

- 10 This invention relates to improvements in machines designed particularly for folding sheets of paper of comparatively small size, such as circulars, letters, etc.
- 15 It relates to the same general type of machine shown and described in Letters Patent No. 752,853, dated February 23, 1904, granted upon the application of Frederick G. Nind and Charles F. Strasburger, and Letters Patent No. 802,057, dated October 17,
- 20 1905, granted upon the application of Frederick G. Nind and myself, —viz., a machine in which the initial fold is imparted to the sheet by a pair of suitable folding rolls and the remaining two folds to the then once-folded sheet by sharply bending them over the edges of a plate extending longitudinally of the machine. In the machine as now constructed, this plate under which the sheet of paper passes and over the edges of which
- 25 it is turned is supported by an arm extending out from a cross-bar near the front of the machine, said bar being connected to a raised central portion of the plate that forms a housing for a series of small pressure rollers that coöperate with positively-driven means that carry the sheet through the machine. The once-folded sheet of paper as it passes through the machine has its side portions turned over this longitudinal housing
- 30 and it has been found that by reason thereof it will not be presented to the pressing devices near the delivery end of the machine in position to have imparted to it two parallel folds, as should be the case of course.
- 35 This is due to the fact that the rear portion of the sheet is still embracing or lying over the housing at the time that the leading end of the sheet is caught between the two paper-engaging rolls that act to move the sheet
- 40 through the final edge pressing devices preparatory to discharging it from the end of the machine. These two paper-engaging rolls just mentioned have heretofore exerted

a constant pressure on the moving sheet and hence have not allowed the turned side portions of the sheet after it passes clear of said housing to settle evenly on top of the portion of the plate in front of said housing.

55 A leading object of this invention is to overcome that objection, and it is accomplished by providing that the upper roll, —viz., that one that acts upon the turned over or side wings of the sheet, —shall engage the paper intermittently, thus giving to the said side wings of the sheet opportunity to gradually assume a proper position on top of the plate whereby the sheet may have imparted to it sharp creases exactly along the lines of the crease just imparted to it by the edges of said plate around which it has been turned.

60 A still further object is to provide improved means for moving the sheets through the machine, and to improve generally in various details of construction and operation 75 machines of this general character.

70 I accomplish these objects by the means shown in the drawings and hereinafter particularly described.

That which is believed to be new will be 80 pointed out in the claims.

In the drawings: —Figure 1 is a top or plan view of my improved machine, the mechanism for supporting the piles of sheets adjacent to the pair of rolls that impart the 85 initial fold to each sheet and the means employed for feeding the sheets to such rolls not being shown. Fig. 2 is a longitudinal vertical section through the central portion of the machine. Figs. 3 and 4 are enlarged 90 cross sections taken substantially at lines 3—3 and 4—4 respectively of Fig. 1. Fig. 5 is a perspective view of a properly folded sheet of paper as produced by the improved machine shown. Fig. 6 is a detail, being a 95 cross-sectional view similar to that of Fig. 3, but illustrating a modified construction wherein a solid forwarding roll is employed on top of the sheet near the discharge end of the machine, and showing the means employed for giving it an intermittent action on the sheet, and Fig. 7 is an end view of the devices of Fig. 6.

100 Referring to the several figures of the drawings, in which corresponding parts are 105 indicated by like reference characters: —10

indicates the side bars of the frame, the same consisting preferably of angular-shaped pieces, the horizontal portions of which form the bed of the machine, between which and the overlying plate hereinafter referred to the sheets of paper pass after receiving their first fold. The front ends of the side bars are united by a heavy cross-head 11 which projects for a considerable distance at each side of the side bars, as clearly shown in Fig. 1. At the other end of the machine, the side bars are united by a plate 12, the upper surface of which is flush with the horizontal portions of the angular side bars, such plate 12 forming really a portion of the bed plate of the machine. The cross-head 11 has at each end two upwardly-projecting arms 13 to the rear faces of which is bolted or suitably secured a heavy cross-bar 14. The parts 10, 11, 12 and 13 are preferably formed of a single casting, although they may of course be separately made and suitably united.

15 indicates a plate preferably formed of a thin smooth sheet of steel arranged longitudinally of the machine and slightly above the bed. For the greater portion of its length, it is provided centrally with a long housing 16 upon its upper side. This housing may advantageously be formed integral with the plate 15 by being struck up from the same. The plate is held in position over the bed plate of the machine by a long bracket 17 projecting rearwardly from the bar 14 with which it may advantageously be integrally formed. This bracket 17 lies over and in contact with the top face of the housing 16, such housing being secured to the bracket in any suitable manner.

40 18-19 indicate rolls in front of the cross bar 14, said rolls being suitably journaled and adapted to give the initial central fold to sheets that are fed between them. Any suitable means for holding the sheets in front of these rolls may be employed, but as such means form no part of my present invention I have not deemed it necessary to illustrate them. Preferably the roll 18 will be a comparatively large roll of yielding material and corrugated lengthwise as shown, while the other roll 19 will be smooth and preferably of metal.

20 indicates an endless belt the upper part of which moves in the space or slot in the bed of the machine between the edges of the horizontal portions of the side bars. This belt passes around two drums, one near the forward end of the machine, which is indicated by 21, and one near the rear or delivery end of the machine, which is indicated by 22. The drum 21 is suitably secured to a long shaft 23 journaled in the side bars 10 and further journaled in a rearwardly-projecting bracket 24 formed with 65 or secured to the cross head 11 (see Fig. 1).

On the end of this shaft 23 is secured a driving wheel 25. This shaft 23 also carries a gear wheel 26 which meshes with another gear whereby the two folding rolls 18-19 are suitably driven. On the opposite end of the shaft 23 from that on which is located the operating wheel or pulley 25 is secured a bevel gear 27 that meshes with another bevel gear 28 fast on a shaft 29 which is parallel with and adjacent to one of the side bars. Through other bevel gears 30-31, the shaft 32, on which is mounted the drum 22, is driven by the shaft 29. This shaft 32 is supported in bars 32^a secured to the inner faces of the side bars 10 and forming prolongations thereof. It is evident of course that the side bars 10 might be long enough and deep enough to properly receive and support this shaft 32 and thus dispense with the separate bars 32^a bolted to them.

33 indicates a series of small rollers suitably journaled in place beneath the slot or space in the bed of the machine and arranged to suitably support the endless belt 20 so as to maintain its upper portion substantially horizontal. The pins or studs on which these rollers are mounted are, in the construction shown, secured in longitudinal bars that are secured to the inner faces of the side bars 10, these bars being indicated by 34.

35 indicates a series of pivoted arms, lying within the housing 16, each arm having mounted in its free end a small pressure roller 36 adapted to bear against the paper carried through the machine by the belt 20. The rollers are placed over the other rollers 33, as shown. Each arm 35 is pressed downwardly by a small spring 37, the free end of which bears against the upper part of the housing 16.

38 indicates arms rigidly secured to the cross head 11 of the machine and extending diagonally toward the rear and over the bed of the machine, one being located near each side thereof. Each arm 38 has adjustably secured to it blades 39 which are adapted to come in contact with the side portions or wings of the sheets of paper being passed through the machine and turn them toward each other. As shown, each of these blades 39 is secured to its respective rigid arm 38 by means of a set screw 40. I have found it advantageous to make these blades or arms 39 adjustable so as to insure the proper turning of the sides of the sheets under varying conditions or kinds of paper.

41 indicates vertical guide strips set apart from each other a distance substantially equal to or a trifle greater than the width of the folded sheet, these guide strips being adjustable to a slight extent toward or away from the longitudinal center of the machine. This adjustability is accomplished by providing each strip with a small slotted se-

curing plate 42 near each end, through which passes a set-screw 43 into the side bars 10 of the machine. To the inner face of each of these guide strips 41 is secured 5 a presser bar 44, which, at its rear end, is parallel with and but slightly raised above the plate 15 but which at its forward end is turned to stand a suitable distance above such plate. The turned sides or wings of 10 the sheet enter at their edges beneath the projecting ends of these presser bars, and as the sheet is advanced they are pressed more and more between such bars and the plate to crease them sharply so that they will be 15 sharply folded when they leave the machine.

When a sheet enters the machine, it will of course be folded once by the rollers 18-19, and, as it passes between such rollers it will, with its folded edge in advance, 20 pass beneath the plate 15, and, as it is carried along by the belt 20, the projecting sides or wings of the sheet will be turned up sharply by the arms 38 and will be turned over toward each other by the arms 25 39 that form continuations of such arms 38, and will be creased slightly along parallel lines by the edges of the plate. In this turned over condition, the sheet will be directed beneath the strips 44 by the arms 39.

30 By the time the leading edge of the sheet has passed to a point where the presser bars become substantially parallel with the plate 15, the rear portion of such sheet will be still bulged out by reason of its still lying 35 over or surrounding the rear portion of the housing 16 as is very clearly shown in Fig. 4. It is necessary to provide further means for advancing the partially folded sheet to the delivery end of the machine, and it has 40 been customary to provide two ordinary rolls or rollers to grip the sheet for this purpose, but a very serious objection to this method of forwarding the sheet is that with the folded-over sides of the sheet tightly 45 gripped at the leading end and bulged out at the rear end there would be no opportunity for the sheet as it progressed to settle 50 flatly and squarely so that the two side folds would be parallel. Indeed, the effect of such firm gripping on these overlying portions of the sheet would be to make the two side folds out of line with each other.

I overcome this very serious objection by providing, in lieu of a solid roll or roller to 55 engage the overlying portions or flaps of the sheet, a device for engaging the sheet intermittently. In the construction shown, except in Figs. 6 and 7, this device is in the form of a toothed wheel or star wheel, the 60 teeth at their outer ends being quite a distance apart so that as one tooth passes out of contact with the upper part of the folded sheet there will be a very brief interval of time before the succeeding tooth strikes it, 65 and this intermittent contacting of the device

with the paper will be sufficient to allow the turned over sides, as the sheet is drawn along, to settle by almost imperceptible but rapid movements so that the entire portions of the overlying wings or flaps of the paper will so settle into place that the sheet as a whole will be drawn perfectly straight toward the delivery end of the machine and have its two folds sharply made along the lines of the crease imparted by the paper having been turned over the edges of the plate 15. Such properly folded sheet is shown in Fig. 5 and designated "A." This intermittently-acting device referred to is indicated by 45, and it is secured to a shaft 46 that lies across and over the machine near its discharge end, such device 45 being located over the large roll 22, around which the endless belt 20 passes. The shaft 46 is provided at one end with a pinion 47 that engages a gear 48 fast on the shaft 32 upon which is mounted the drum 22.

49 and 50 indicate a pair of rolls through which the folded sheet passes and which act to more sharply fold the sheet along the lines which have been already creased and pressed upon.

The shaft 46 is mounted in bearings that are secured to the free ends of arms 46^a, the other ends of which arms are securely fastened by screws, as shown in Fig. 1 or otherwise, to the horizontal portions of the side bars 10. Through each arm 46^a, near the said shaft bearings, passes a set-screw 46^b, the ends of which set-screws engage the side bars 10 immediately beneath. By means of these screws the shaft can be adjusted higher or lower very slightly to regulate the degree of pressure with which the device 45 will bear upon the paper. Of course the adjustment can only be a slight one in view of the engagement of the pinion 47 on said shaft with the gear 48.

In Figs. 6 and 7, I have shown a modification in the construction of the intermittently acting device that bears upon the upper portion of the folded sheet. In this construction I employ a solid roller 51. At the end of the shaft 46 opposite that which carries the pinion 47, I provide a slotted journal-bearing 52 in which that end of the shaft 46 is mounted, and, to the end of the said shaft I loosely secure an arm 53 the other end of which arm engages a pin 54 placed eccentrically upon a pinion 55 that is in mesh with a gear 56 on the projecting end of the shaft 32. This mechanism will cause the roller 51 to intermittently engage the upper portion of the sheet and allow of the slight moving in of the folded over portions of the sheet so as to lie perfectly smooth and straight, the same as described for the other construction shown in the other figures. The bearing for the shaft 46 adjacent to the pinion 47 will necessarily have 130

4
to be enlarged slightly as shown in Fig. 6, to permit of the slight rise and fall of the shaft 46.

What I claim as my invention and desire

5 to secure by Letters Patent is:—

1. In a paper-folding machine, the combination with a plate having a raised central portion to form a housing and means for moving a sheet of paper along one face of said plate with the side portions of said sheet extending beyond the plate, of means for turning such side portions over the edges of the plate and over such central housing, pressure devices within the housing adapted 10 to bear upon the central portion of the moving sheet, and means over the path of the sheet and beyond the rear end of said housing adapted to intermittently bear upon the turned over portions of the sheet.

20 2. In a paper-folding machine, the combination with a plate having a raised central portion to form a housing and means for moving a sheet of paper along one face of said plate with the side portions of said sheet extending beyond the plate, of means for turning such side portions over the edges of the plate and over such central housing, pressure devices within the housing adapted 25 to bear upon the central portion of the moving sheet, and rotating means over the path of the sheet and beyond the rear end of said housing adapted to intermittently bear upon the turned over portions of the sheet and aid in moving said sheet toward the delivery end of the machine.

3. In a paper-folding machine, the combination with a plate and means for moving a sheet of paper along one face of said plate with the side portions of said sheet extending beyond the plate, of arms secured 40 to the frame of the machine and adapted to cause the said side portions of the moving sheet to be turned upward, and another arm adjustably secured to each of said first-named arms and adapted to cause a further turning of said side portions of the sheet.

4. In a paper folding machine, the combination, with a plate having a housing, of means within the housing for moving a sheet of paper along one face of said plate with the side portions of the sheet extending beyond the opposite edges of the plate,

means for turning both such side portions over the edges of the plate to make a three-panel fold, and a member acting intermittently on one of the extreme panels while the sheet is around said plate and while the line of fold of such panel is free to move inwardly.

5. In a folding machine, the combination 60 of a former plate having an intermediate trough-like housing, a series of arms pivotally mounted within such housing, rolls carried by said arms, and springs bearing against said arms and the face of the trough-like portion of the housing.

6. In a folding machine, the combination 70 of a series of forwarding rolls, an endless belt traveling over the same, a series of rolls opposite the rolls mentioned and co-operating with the belt, a series of arms in alignment carrying the rolls last referred to, and a former plate having an intermediate trough-like housing, said arms being pivotally mounted in said housing, and said belt 75 being opposite an open entrance to the housing.

7. In a folding machine, the combination, with a former plate having an intermediate longitudinal trough-like housing projecting 80 from it and open in the plane of the plate, a series of propelling rolls within the housing and effective at the open edge of the trough, co-operating movable propelling means on the other side of the plate, and means for folding the projecting portions of the sheet over the edges of the former plate, the housing being closed on its outer side to protect the folded portions of the sheet from the internal rolls.

8. In a folding machine, the combination 90 of a continuous former plate bent intermediate to present a central longitudinal housing and two projecting portions in the same plane, propelling rolls within the housing, 95 co-operating propellers on the opposite side of the former plate, and folding means for bending the projecting portions of a sheet across the edges of the former plate and over the housing.

FREDERICK JULYAN.
